(57) **CLAIM**

I claim the ornamental design for a neck gaiter tube, as shown and described.

DESCRIPTION

FIG. 1 is a perspective view of a neck gaiter tube, showing my new design as worn by a person;

FIG. 2 is a perspective view thereof in a flat configuration;

FIG. 3 is a front elevational view of the design as shown in FIG. 2;

FIG. 4 is a rear elevational view of the design as shown in FIG. 2;

FIG. 5 is a top plan view of the design as shown in FIG. 2, the bottom plan view being a mirror image thereof;

FIG. 6 is a left-side elevational view of the design as shown in FIG. 2, the right-side elevational view being a mirror image thereof; and,

FIG. 7 is a rear elevation view of the design as shown in FIG. 2 but in an inside-out configuration.

The broken lines showing a person in FIG. 1 and a logo in FIGS. 1-3 depict environmental matter and form no part of the claimed design.
